UNITED STATES PATENT OFFICE.

EDWARD N. LA VEINE, OF KANSAS CITY, MISSOURI.

DESIGN FOR A GARMENT-SUPPORTER.

SPECIFICATION forming part of Design No. 30,918, dated May 30, 1899.

Application filed May 1, 1899. Serial No. 715,242. Term of patent 7 years.

To all whom it may concern:

Be it known that I, EDWARD N. LA VEINE, of Kansas City, Jackson county, State of Missouri, have invented a new and original Design for Garment-Supporters, of which the following is a full, clear, and exact description, reference being had to the accompanying drawings, forming a part hereof.

Figure 1 is a plan view of a garment-supporter embodying my new design. Fig. 2 is a side elevation of the garment-supporter, and Fig. 3 is a rear end elevation thereof.

As shown in the drawings, the leading or material feature of my design consists of a flat body 1, the front end 2 of which is gradually widened to its terminus, and the extreme forward end of said body 1 is bent upwardly and then rearwardly to form the transverse bead or rib 3. The rear end of the body 1 is formed slightly wider than the center of said body, and said rear end is turned upwardly at right angles to said body 1, and the center of said upwardly-turned rear end is cut out, so as to form the prongs or projections 4, the upper ends of which are slightly bent forwardly. Extending upwardly from the sides of the body 1, just to the rear of the

center thereof, are the ears or projections 5, upon which is arranged the body 6, the same being almost identical in form with the body 1, the extreme forward edge of said body 6 being bent downwardly and then rearwardly to form the transverse rib or bead 7, which rests directly upon the rib or bead 3. The body 6 is bent double at its rear end, the doubled-back portion 8 occupying a plane just above that occupied by the body 6, and the forward portion of the doubled-back end 8 terminates in a circular disk 9. Formed in the disk 9 is a triangular aperture 10, and extending downwardly from said disk 9, immediately in front of said aperture 10, is a lug 11, the same resting directly upon the top of the body 6.

I claim—

The design for a garment-supporter, substantially as herein shown and described.

In testimony whereof I affix my signature in presence of two witnesses.

EDWARD N. LA VEINE.

Witnesses:

EMMA LOGAN,
ROSS T. THOMAS.
